MACHINE FOR OPERATING INTERMITTENTLY UPON AND IN SYNCHRONISM WITH A CONTINUOUSLY FLOWING STREAM OF MATERIAL

Edward Skillman, Enterprise, Kans., assignor to
The J. B. Ehksam & Sons Manufacturing Co.,
Enterprise, Kans., a corporation of Kansas

Application March 8, 1951, Serial No. 214,582

12 Claims. (Cl. 164—43)

1

The present invention relates to a machine for variably operating on continuously-flowing material. The invention is adapted for use in connection with a shear, a punch, printing or embossing mechanism, a scoring device, or any one of a multitude of applications in which it is desired to perform some operation, at fixed or variable intervals, upon a continuously-flowing stream of material which may or may not move at constant velocity. For convenience of description, the invention has been illustrated as embodied in a flying shear, but it is to be understood that such illustration is by way of example only and is not intended to be limitative.

When a continuously-movable stream of material is to be operated upon in any type of work analogous to those above suggested, it is essential that, during operative engagement between the work and the parts of the machine acting upon the work, those parts shall be moving, in the direction of movement of the work, and, with reasonable accuracy, at the velocity of the work. Such synchronization is, of course, impossible to attain through a simple eccentric drive, effected by mounting the cooperating parts of the machine upon diametrically opposite crank portions of a rotor, since the velocity of such parts, in the direction of movement of the work, imparted by such crank elements, is continuously variable throughout the cycle of the rotor. An object of the present invention is to provide means of novel characteristics for modifying the velocity of parts so supported in order to attain substantial uniformity of velocity thereof, in the direction of work movement, during a period of cooperative engagement between such parts and the work.

A further object of the invention is to provide novel means, in connection with such a machine, for varying the effect, upon a pair of cooperating elements so mounted, of rotation of the supporting rotor whereby, at times, such rotation will move the jaws into one cooperative relation to the work and, at other times, will move said jaws into a different cooperative relation with the work. The character of such means, as disclosed herein, may be such as completely to prevent cooperation between such parts and the work throughout any desired number of cycles of the rotor, and to effect such cooperative relation during the next cycle succeeding such predetermined number of cycles; or, alternatively, it may be such as to cause a pair of cooperating shear jaws to score the work material upon each of such predetermined number of cycles, and to sever the work material upon the next succeeding cycle.

A still further object of the invention is to provide means for selectively varying the rate of

5 rotation of such a rotor, relative to the velocity of the flowing work material, in order to vary the spacing between work-affecting operations of the machine, in the direction of length of the flowing work stream.

Still further objects of the invention will appear as the description proceeds.

To the accomplishment of the above and related objects, my invention may be embodied in 10 the form illustrated in the accompanying drawings, attention being called to the fact, however, that the drawings are illustrative only, and that change may be made in the specific construction illustrated and described, so long as the scope 15 of the appended claims is not violated.

Fig. 1 is a side elevation of a machine constructed in accordance with the present invention as seen from a position in which the work stream flows from the observer's left toward his right;

20 Fig. 2 is an end elevation of said machine seen from the right-hand end of Fig. 1, parts being shown in section for clarity of illustration;

Fig. 3 is a horizontal section taken substantially on the line 3, 3 of Fig. 1;

25 Fig. 4 is an enlarged longitudinal fragmental section taken substantially on the line 4, 4 of Fig. 3;

Fig. 5 is a view similar to Fig. 4, but showing the parts in a different relationship;

30 Fig. 6 is a view similar to Fig. 1 but taken from the opposite side of the machine, parts being removed or shown in section for clarity of illustration;

Fig. 7 is an end elevation taken from the left of Fig. 1;

35 Fig. 8 is a longitudinal fragmental section, taken substantially on the line 8, 8 of Fig. 3 and drawn to an enlarged scale;

Fig. 9 is an exploded perspective of one form 40 of variable crank mechanism which may be used in my invention;

Fig. 10 is an elevation taken from the left-hand end of Fig. 8; and

Fig. 11 is an elevation of one element of the machine.

45 Referring more particularly to the drawings, it will be seen that I have illustrated a base 10 providing an upstanding support 11 in which is journaled a transversely-extending shaft or rotor 12. Immediately beyond the ends of said support, the shaft is provided with aligned crank sections or eccentrics 13; and, beyond said sections, said shaft is provided with further crank sections or eccentrics 14. As illustrated, the sections 14 are peripherally spaced 180° from the sections 13, and the degree of eccentricity of said portions 14 is equal to the degree of eccentricity of

the sections 13. Between the sections 13 and 14, at one or both ends of the shaft 12, there is provided a further eccentric section 15 which, as shown, may be of substantially less degree of eccentricity. The function of the section 15 will appear as the description proceeds.

A jaw member 16, having a work-cooperative portion 17 near one end thereof, is provided, in the illustrated embodiment of the invention, with laterally-separated, downwardly-turned leg portions 18 (Fig. 2) adjacent its said end, said leg portions being journal mounted, respectively, upon the eccentric sections 13, 15 of the shaft 12.

A further pair of supports 19, 19 are mounted near the opposite end of the base 10, and each is formed to provide a trackway 20 therein, as is most clearly shown in Figs. 1 and 6. At its corresponding end, the jaw member 16 is provided with a pair of laterally-separated, downwardly-extending legs 21, 21, each of which carries a pintle 22 mounting a roller 23 engaged and supported in one of said trackways for reciprocatory movement therein. The details of the trackways 20 and the operation of the rollers 23 therein will be discussed hereinafter.

Directly above the pintles 22, the jaw member 16 is provided, at each lateral side thereof (Fig. 7) with a laterally-offset boss 24 in which is received a hinge pin 25. An upper jaw member 26 is provided at its rear end with downturned legs 27, spaced to mate with the bosses 24 and perforated to receive the hinge pins 25. Thereby, the jaw members 16 and 26 are hingedly connected at their rear ends for relative movement about the common axis of the hinge pins 25. At its opposite, or forward, end, the jaw member 26 is provided with a work-cooperative portion 28 positioned for coaction with the portion 17 of the jaw 16. In the illustrated embodiment of the invention, the units 17 and 28 may be shear blades; but it will be understood that they may be any other kind of cooperating tools, and that they, or either of them, may be integral with, or removably carried by, the respective jaws, all in accordance with the broad concept of the invention as stated above.

The forward end of the jaw member 26 is formed to provide laterally-separated journal bearings 29, 29 in which is mounted a rock shaft 30 provided, at its opposite ends and beyond the bearings 29, with aligned eccentric portions 31, 31 disposed in registry with the cranks 14, 14 of the shaft 12. Fixed to the rock shaft 30 at a suitable point is an arm 32 (Fig. 1) and a link 33 has one end pivotally connected to the arm 32 and its opposite end pivotally connected to a plunger 34 reciprocably mounted in a housing 36 and resiliently urged to its illustrated position by a spring 35. The tubular housing 36 is mounted to rock about a pivot 37 carried by a support 38 mounted on the jaw member 26.

It will be seen that the elements 32, 33, 34 comprise a toggle and that the spring 35 tends to retain that toggle resiliently in either of its opposite positions. If the link 33 is moved upwardly from its illustrated position, the plunger 34 will be forced inwardly against the tendency of the spring 35, and the housing 36 and the arm 32 will be oppositely rocked about their respective journal mountings until they pass a position of alignment, whereafter the spring 35 will tend to continue such upward movement of the link 33 to force the arm 32, in a clockwise direction, to the limit of such movement. This action of the toggle will turn the rock shaft 30, in a clockwise

direction as viewed in Fig. 1, through approximately 90°, thereby shifting the eccentrics 31, 31 from positions, as shown, below the axis of the rock shaft 30 to positions above that axis.

A rigid strap 39 is provided for supporting each end of the rock shaft 30 from the rotor 12. Each such strap has its lower end 40 journalled on one of the cranks 14, and its upper end 41 journalled on one of the eccentrics 31. Thereby, the forward end of the jaw member 26 is supported from the cranks 14, 14.

In Fig. 1, the cranks 13 are shown at the tops of their circular paths, while the cranks 14 are shown at the bottoms of their circular paths. Thus the tool 17 is in its uppermost position, within the cycle of the rotor 12, and the tool 28 is in its lowermost position, within that cycle. As will be seen, so long as the rock shaft 30 is in its position shown in Fig. 1, the tools 17 and 28 are spaced from cooperative relation. If, however, the rock shaft 30 is turned to the opposite limit of its adjustment, in the manner illustrated in Fig. 6, the axis of the rock shaft 30 will thereby be thrown below the axis of the cranks 31, whereby, with the shaft 12 in its position shown in Fig. 1 and in Fig. 6, the tools 17 and 28 will be brought into cooperative relation.

Power is supplied to the machine through an input shaft 42 (Fig. 3) which may, in any desired fashion, be driven in synchronism with the stream of material being fed to the machine of the present disclosure, whether that stream moves at uniform, or at variable, speeds. Said shaft 42 is suitably journalled upon the base 10, and delivers power to a differential mechanism. As shown, said mechanism comprises a housing 43 normally held against rotation about the axis of the shaft 42 by any suitable brake 44 calibrated to exert upon said housing a predetermined braking effect. The brake, however, must be of such character as to permit rotation of the differential housing 43 under the influence of mechanism later to be described.

The shaft 42 carries a beveled gear 45 within the housing 43, said gear meshing with pinions 46, 46 journalled in said housing, and said pinions meshing, also, with an output gear 47 carried, within said housing, upon an output shaft 48 journalled in suitable bearings supported upon the base 10. A sprocket 49 fixed to the shaft 48 drives, through a chain 50, a sprocket 51 fixed to the shaft 12.

The operation of the mechanism thus far described is as follows. Assuming the rock shaft 30 to be in the position of Fig. 6, power supplied through the shaft 42 will be transmitted, at the speed of said shaft and in the opposite direction, to the rotor 12. As said rotor turns, in a clockwise direction as viewed in Fig. 1, the cranks 13 move toward the right and downwardly, while the cranks 14 move toward the left and upwardly. Thereby, the right-hand end of the jaw member 16 is carried toward the right at a decreasing velocity, and is carried downwardly at an increasing velocity. Since the left-hand end of the jaw member 26 is hinged to the left-hand end of the jaw member 16, the right-hand end of the jaw member 26 will move toward the right with the right-hand end of the jaw member 16; but as the cranks 14 move upwardly, the right-hand end of the jaw member 26 will move upwardly at a rate corresponding to the rate of downward movement of the right-hand end of the jaw member 16.

Since the hinge axis between the jaw members

is spaced upwardly from the pins of the pintles 22, the movement of the jaws in response to the travel of the cranks 13 will cause the hinge axis 25 to rock in a clockwise direction about the axis of the pintles 22. Such rocking movement, of course, producing a transaxial movement of the hinge pins 25 toward the right, will incrementally increase the rate of movement of the tools 17 and 28 toward the right.

In the illustrated embodiment of the invention, it will be seen that the jaw member 16 will move bodily toward the right, under the influence of the cranks 13, throughout the upper half of the rotary path of travel of said cranks; and in that illustrated embodiment, the pintles 22 are mounted for reciprocatory travel, generally in the direction of flow of the work material. The trackways 20 are designed, in the illustrated embodiment of the invention, to compensate accurately for the variation in the velocity of longitudinal movement of the jaw member 16 resulting from the rotary path of the cranks 13, in a machine in which the distance from a vertical plane common to the axes of the pintles 22 and the pins 25 to the vertical plane common to the axes of the rotor 12 and rock shaft 30 is three times the distance from the axis of the eccentric 13 to the active surface of the tool 17, and in which one revolution of the shaft 12 corresponds to one foot of travel of work material through the machine. As shown, each such trackway comprises four sections; a circular arcuate section 128 thrown upon a radius of 1.6", a rectilinear portion 129 tangent to the portion 128, a circular arcuate portion 130 merging with the opposite end of the section 128 and thrown upon a radius of 4½", and a rectilinear portion 131 tangent to the opposite end of the portion 130. This specific, numerically-limited trackway design is, of course, applicable only to the specified set of conditions; but of course said trackway can be made of a contour to fit any special conditions, and thereby to cause the travel of the tools 17 and 28 to correspond, during engagement thereof with the work, accurately to the rate of travel of such work throughout a considerable distance. The specific dimensions herein illustrated will result in substantially perfect synchronization throughout 60° of travel of the shaft 12, during which time the rollers 23 will traverse the sections 128 and 130 of the trackways. The rectilinear portions 129 and 131 of said trackways, of course, are not critical.

In installations not requiring such a high degree of accuracy, the pintles 22, or the bosses 24, may be supported pivotally at the upper ends of links or hinge elements mounted to oscillate about a common axis parallel with the axis of the rotor 12.

So long as the differential housing 43 is held against rotation, the rotation of the shaft 12 will be directly synchronized with the flow of material through the machine, and the tools 17 and 28 will be caused to approach each other (for instance) once for every foot of travel of the work material therewith. It is sometimes desirable to vary the frequency of such approach, relative to the velocity of the work stream; and I have provided means for controllably effecting such variation.

The shaft 42 carries a gear 52 meshing with a gear 53 loosely journalled upon a shaft 55 and driving a single-revolution clutch 54 adapted, when tripped, to establish a driving connection between the gear 53 and the shaft 55. The spe- 75

cific construction of the clutch 54 is impertinent to the present invention, so long as its construction is such that, when it is tripped, it engages the gear 53 to drive the shaft 55 through one revolution and then releases such engagement until the clutch is tripped again.

An arm 56 (Fig. 8) is fixed to the shaft 55 in any suitable manner, and projects radially therefrom. Said arm is formed to provide a guideway 57 in which is suitably supported a trunnion member 58 for movement, along said trackway, between a position radially remote from the axis of the shaft 55 and a position coaxial therewith. Suitable means 59 is provided for retaining on said trunnion, in journalled relation, a collar 60 rigid with a rack 61. The details of the arm 56 and the manner in which it supports the trunnion element 58 adjustably will be more fully described hereinafter. For the present, suffice it to say that the arm and trunnion element comprise crank means, driven with the shaft 55, operatively connected to reciprocate the rack 61, and adjustable between zero throw and a predetermined maximum.

By means of a cradle 62 or any other suitable device having a comparable function, the rack 61 is supported in meshing engagement with a pinion 63 coaxial with the differential housing 43. One-way clutch means, indicated generally by the reference numeral 64, is interposed between the pinion 63 and the differential housing 43, providing a driving connection between the pinion 63 and said housing, upon rotation of said pinion in one direction, but leaving said pinion free to rotate in the opposite direction relative to said housing. As shown, the pinion 63 may have a hub telescopically associated with a hub 65 on the housing 43, said pinion providing cam pockets in which are received balls or rollers 66 engaging said housing hub, in a manner well known to the art and illustrated in Fig. 8. As shown, the pinion 63 is free to rotate in a clockwise direction relative to the housing 43, as seen in Fig. 8, but will carry said housing with it upon rotary movement in a counter-clockwise direction. Obviously, when the shaft 55 is turned in a clockwise direction from its position illustrated in Fig. 8, the rack 61 will be moved toward the right throughout the first half revolution of the shaft 55 to drive the pinion 63 and housing 43 in a counter-clockwise direction; and said rack will move toward the left throughout the second half of such revolution of the shaft 55, carrying the pinion 63 in a clockwise direction, but leaving the housing 43 undisturbed.

If the parts are so proportioned and designed that such reciprocatory cycle of the rack 61 produces one-half revolution of the housing 43, it will be seen that the shaft 12 will thereby be retarded by one full revolution, so that the length of work material passing the jaws between cycles thereof will be increased by one foot. This movement of the housing 43 is, of course, timed to occur during a period when the tools 17 and 28 are separated from each other and from the work, so that the consequent temporary reduction in velocity of the shaft 12 relative to the velocity of the work stream has no deleterious effect.

Obviously, a slight rearrangement of the parts would result in acceleration of the shaft 12, in response to an operative cycle of the rack 61, to shorten the time between actions of the jaws.

It will be clear that, as the trunnion element 58 is adjusted, from its illustrated position, to-

ward the axis of the shaft 55, the throw of the rack 64, in response to a revolution of the crank, will be incrementally decreased, whereby the effect of the rack cycle upon the length of the jaw cycle will be correspondingly decreased; and it will further be seen that, if the trunnion element 58 is moved into axial coincidence with the shaft 55, the rack will be held stationary and the cycle of the jaws will be unaffected by rotation of the shaft 55.

One form of means for adjusting the position of the trunnion element 58 in the trackway 57 is illustrated in Figs. 3, 8, 9 and 10. Axially slidably mounted on the shaft 55 is a collar 67 which may or may not rotate with the said shaft. A screw shaft 68 is journalled for rotation on an axis parallel with the axis of the shaft 55, and a nut 69 is threadedly mounted on said shaft 68, being suitably held against rotation therewith. A yoke 70, having a portion operatively engaged in a groove in the collar 67, is operatively connected to the nut 69, whereby rotation of the screw shaft 68 will shift the collar 67 axially along the shaft 55.

A bracket 71 is mounted to rotate with the shaft 55, and, at a point remote from the axis of said shaft, carries a pivot pin 72 upon which is rockably mounted a lever 73, one arm 74 of which has a portion engaged in a groove in the collar 67, whereby axial movement of said collar will oscillate the lever 73. The other arm 75 of the lever 73 is connected to one end of a link 76, the opposite end of which is operatively connected to the trunnion member 58. A hand wheel 77 is carried by the screw shaft 68 at an accessible point. In the illustrated embodiment of the invention, the yoke 70 may comprise a lever pivotally mounted at 73, intermediate its ends, upon a standard 79 fixed to the base 10, and having its end remote from the collar 67 pivotally connected with the nut 69. Obviously, rotation of the hand wheel 77 will adjust the throw of the crank trunnion 58 to vary the length of the stroke of the rack 64, thereby varying the degree of rotation of the housing 43 resulting from each rotation of the shaft 55.

I have provided adjustable means for actuating the rock shaft 39 to determine the degree of approach of the tools 17 and 28 toward each other within the cycle of the jaw members 16 and 26. A plate 80, suitably secured to the base 10 and upstanding therefrom (Figs. 1 and 3), is provided with a peripheral series of perforations 81 concentric with an opening in which is journalled a shaft 82, said shaft being further journalled in a bracket 83. A coiled spring 84 has one end anchored on the bracket 83 and has its opposite end anchored on the shaft 82, whereby said spring tends always to rotate said shaft 82 in a clockwise direction as viewed in Figs. 4 and 5, and resiliently to resist turning movement of the shaft 82 in a counterclockwise direction.

Loosely journalled for oscillation about the axis of the shaft 82 is a lever 85 having arms 86 and 87 projecting radially therefrom and angularly spaced from each other by about 90° (Figs. 4 and 5). An adjusting arm 88 is likewise loosely journalled on the shaft 82, in front of the plate 80, and carries a handle 89 in which is mounted a knob 90 connected to a plunger 91 reciprocable in the handle 89 and spring pressed to its projected position as shown in Fig. 3, the tip of said plunger being selectively enterable in any one of the perforations 81 to hold the arm 88 in any desired position of adjustment. A finger 93 is

keyed to the shaft 82 behind the plate 80 and a finger 94 is keyed to said shaft in front of said plate. The arm 87 of the lever 85 carries an adjustable screw 95 for the purpose later to be explained; the arm 93 carries an adjustable screw 96 whose path of movement, with the arm 93, intersects the lever 87; and the arm 94 carries an adjustable screw 97 whose path of movement, with the arm 94, intersects the arm 88. The manner in which these parts cooperate will be described hereinafter.

A collar 98 is journalled on the eccentric 15 of the shaft 12 and is provided with a boss 99 having a threaded socket in which is fixed one end of a pawl 100. Said pawl is reciprocably received between the furcations of a yoke 101 carried at the upper end of a rocker 102 pivotally mounted at 103 upon a suitable support 103' fixed to the base 10. Said rocker is urged resiliently in a counter-clockwise direction, as viewed in Fig. 4, by a spring 104; and a nut 105 adjustably mounted on the pawl 100 is cooperable with the rocker to return the same, against the tendency of the spring 104, to its illustrated position whenever the pawl attains the right-hand limit of its stroke resulting from rotation of the eccentric 15.

A link 106 is pivotally connected to the pawl 109 at 107 near the nose of said pawl; and a pin or roller 108, carried on the lever arm 86, engages in an elongated slot 109 in the remote end of said link. Normally, the free end of the lever arm 86 rests upon a step 110 formed on the rocker 102, as shown in Fig. 4; but said rocker is formed with a further step 111 upon which, under circumstances which will appear hereinafter, the lever arm 86 may alternatively rest, as shown in Fig. 5. A spring 112 resiliently urges the nose of the pawl 100 into cooperative engagement with a ratchet wheel 92 keyed to the shaft 82.

A holding pawl 113, which may be mounted for rocking movement about the pivot 103, is resiliently urged into cooperative engagement with said ratchet wheel by a spring 114; and a spring 115 resiliently resists counter-clockwise movement of the lever 85.

As the shaft 12 rotates, the eccentric 15 and collar 98 will produce reciprocation of the pawl 100. Said pawl is shown, in Fig. 4, substantially at the right-hand end of its path of movement. As the pawl moves toward the left, the engagement of its nose with a tooth of the ratchet wheel 92 will cause said ratchet wheel to be turned one step in a counter-clockwise direction against the tendency of the spring 84, the nose of the pawl 113 clicking over a tooth of the ratchet wheel and engaging behind that tooth to hold the ratchet wheel against return as the pawl 100 moves back to the right. The arm 93 and screw 96 will, of course, move correspondingly with the shaft, whereby the screw 96 will approach the lever arm 87.

Eventually, as reciprocation of the pawl 100 continues, the screw 96 will engage the lever arm 87 to move the lever 85 in a counterclockwise direction, to a position in which the rocker 102 will be permitted to move counterclockwise, under the influence of the spring 104, to engage the step 111 under the lever arm 86.

This relation of the parts, illustrated in Fig. 5, will be attained, of course, as the pawl 100 approaches the left-hand limit of its stroke. The lever arm 86 carries a finger 116 which, as said lever arm rises, engages under the holding pawl 113 to lift the same out of cooperative relation with the ratchet 92. Now, only the pawl 100

holds the ratchet wheel 92 and shaft 82 against clockwise rotation under the influence of the spring 84. As the pawl 100 starts its return movement to the right, the link 106 acts as a toggle, when the upper end of its slot 109 engages the pin 108, to lift the pawl 100 out of engagement with the ratchet to permit the spring 84 to turn the shaft 82 and its associated parts in a clockwise direction. Such movement of the shaft and its associated parts is limited by engagement of the screw 97 on the arm 94 with the arm 88, in its current selected position. This shaft movement is very quick and occurs before retractile movement of the nut 105 on the pawl 100 shifts the rocker 102 sufficiently to permit the lever arm 86 to drop off the step 111 and return to the step 110, thereby permitting the holding pawl 113 to return to cooperative relation with the ratchet 92.

A link 117 connects the screw 95, carried by the lever arm 87, with a rocker 118 fixed to a rock shaft 119 journaled in suitable bearings and extending transversely of the base 10. When the lever arm 87 is moved in a counterclockwise direction by the screw 96, as above described, from the position of Fig. 4 to the position of Fig. 5, the rock shaft 119 will be correspondingly turned.

Near its end remote from the rocker 118 (Figs. 3 and 6), the rock shaft 119 carries a rocker 118'. A plunger 120 has one end pivoted to the rocker 118' and is reciprocably mounted in a tubular element 121, a spring 122 resiliently urging said element 121 toward the end of the plunger 120 remote from the rocker 118. A latch 123 is carried upon a slide 124 reciprocable upon a rod 125; and the movable end of said latch is connected to the element 121. Thus, so long as the parts are in the positions of Fig. 4, said latch 123 will be held out of cooperative engagement with an abutment 127 secured to the rod 125; but when the parts are moved to the positions of Figs. 5 and 6, the spring 122 will resiliently urge said latch 123 toward cooperative relation with said abutment 127.

A link 126 connects the slide 124 to move with the jaw member 16. The rod 125 is connected to the link element 33 of the toggle which normally moves with the jaw member 26, and the lower end of said rod may be slidably mounted in a suitable guideway 125' in or upon the base 10.

Thus, so long as the lever 85 remains in the position of Fig. 4, the toggle will hold the rock shaft 30 in the position of Fig. 1, and the latch 123 will reciprocate, following the motions of the jaw 16, without affecting the rod 125. When the lever 85 is moved to the position of Fig. 5, however, the latch will be shifted, by the rocker 118', plunger 120 and element 121, and will engage the abutment 127 to lift the rod 125 upon the next upward movement of the jaw member 16, whereby the rock shaft 30 will be turned, in a counterclockwise direction as viewed in Fig. 6, to cause the tools 17 and 28 to move into cooperative relation upon closure of the jaws 16 and 26.

However, as the jaws begin to separate, and the pawl 100 is retracted, the ratchet 92 is released to permit the spring 84 to rotate the shaft 82 to move the screw 96 away from the lever arm 87; and the rocker 102 is shifted in a clockwise direction to permit the lever arm 86 to drop back onto the step 110, whereby the rock shaft 119 is returned to the position of Fig. 4 and the latch 123 is withdrawn from the abutment 127. The slide 124, of course, will positively move the rod 125

5

10

downwardly, as the jaws separate, to return the rock shaft 30 to the position of Fig. 1, and the toggle means 32-36 will hold the rock shaft in this position until the latch 123 is again moved into cooperative relation with the abutment 127.

The shaft 82 and its associated parts will thus be returned to cycle-starting position, which, of course, will depend upon the current position of the adjusting arm 88.

Preferably, the number and spacing of the perforations 81 will correspond to the number and spacing of the teeth of the ratchet wheel 92.

Since it will ordinarily be desirable to actuate the length-modifying device of the present machine only at the time when the tools 17 and 28 are to cooperate, I have herein illustrated means dominated by the rock shaft-actuating means for tripping the single revolution clutch 54 through which the rack 61 is actuated. Alternatively, of course, any desired manual or automatic means may be provided for tripping said clutch. In the illustrated embodiment of the invention, however, the lever 85 may include a further arm 132, connected to operate a rock shaft 133 which, in turn, is connected to actuate a trip lever 134 operatively connected to the clutch 54. Thus, when the lever 85 is shifted by the screw 96, the clutch 54 will be actuated to turn the shaft 55 through a single revolution.

One suitable form of mechanism providing for adjustment of the throw of the rack 61 is illustrated in detail in Figs. 8, 9 and 10. As there shown, the trackway 57 in the arm 56 is guarded by coplanar lips 135 and 136, and is provided with a slot 137 opening through the upper surface of the arm 56. A block 138 is slidably mounted in the trackway; and a removable pin 139 extends from said block through the slot 137, while the trunnion element 58 projects from said block between the lips 135 and 136. An end of the link 76 is pivotally engaged upon the projecting portion of the pin 139 and may be held thereon by a cotter pin 140 or the like; and a screw 141 penetrates the washer 59 and takes into a suitable socket in the free end of the trunnion element 58 to secure said washer in place to hold the collar 60 between said washer and the arm 56. The arm 56 is fixed to a collar 142 sleeved on the shaft 55 and adapted to be secured thereto by a set screw 143, or the like; and said collar may also carry the bracket 71. The trackway 57 and the slot 137 are so proportioned and designed that the path of movement permitted to the block 138 is such that the trunnion element 58 may assume any position between coaxiality with the shaft 55 and a location in which its axis is parallel with, but a maximum radial distance from, the axis of said shaft.

It will be clear from the above that, with the parts adjusted as described, so long as the rock shaft 30 is in the position of Fig. 1, rotation of the shaft 12 will result in vibration of the jaws 16 and 26 without affecting the stream of work material flowing therebetween. When, however, the pawl 100 has advanced the shaft 82 sufficiently to cause the screw 96 to shift the lever 85 to rock the shaft 119, the rock shaft 30 will be shifted to the position of Fig. 6 and, when the jaws next approach each other, the shears 17 and 28 will act to sever the work material. Immediately thereafter, the pawls 113 and 100 will be disengaged from the ratchet wheel 92 and the spring 84 will return the shaft 82 and its associated parts to the positions illustrated in Fig. 4, whereafter the cycle will be repeated.

65

70

75

If it is desired that the work material shall be scored each time the jaws approach each other, while the rock shaft 119 is in the position of Fig. 4, the nut 34' may be turned down upon the plunger 34 to limit the degree of projection of said plunger from the housing 36 under the influence of the spring 35, when the toggle linkage is broken downwardly, so that, when the rod 125 is pushed downwardly by the slide 124, the rock shaft 30 will be stopped in an intermediate position such that, as the jaws approach each other, the shear blades 17 and 28 will engage and score the work material, without severing the work material. Concurrently with adjustment of the nut 34', of course, the abutment 127 will be adjusted downwardly upon the rod 125 and secured in its new position by the set screw 127'. These adjustments, of course, will not affect the operation of the timing mechanism associated with the shaft 82, which will still cause the shear blades to sever the work material at predetermined intervals.

I claim as my invention:

1. In a machine of the character described, a pair of jaw members, instrumentalities either integral with or carried by said jaw members, means hingedly joining said jaw members for relative movement about an axis, means supporting said joining means for vibratory movement transversely of its own axis, a rotor having two diametrically-opposed eccentric portions, means supporting that end of one of said jaw members which is remote from said axis from one of said eccentric portions, and means supporting that end of the other of said jaw members which is remote from said axis from the other of said eccentric portions.

2. In a machine of the character described, a pair of jaw members, means hingedly joining said jaw members for relative movement about a transaxially-movable axis, a rotor having two diametrically-opposed eccentric portions, means supporting that end of one of said jaw members which is remote from said axis from one of said eccentric portions, means supporting that end of the other of said jaw members which is remote from said axis from the other of said eccentric portions, the supporting means for one of said jaw members including adjustable means for varying the effective length thereof to vary the action of said jaw members, means for driving said rotor, an element cooperatively connected with said adjustable means and shiftable to move said adjustable means, latch means movable with the other of said jaw members and normally held out of cooperative engagement with said element, and step-by-step means driven from said rotor and operable, upon attaining a predetermined position, to shift said latch means into cooperative engagement with said element to shift said element.

3. The machine of claim 1 in which said means supporting the joining means is stationary with respect to one of said jaw members.

4. In a machine of the character described, a pair of jaw members, means hingedly joining said jaw members for relative movement about a transaxially-movable axis, a rotor journalled for rotation about a fixed axis, and having two peripherally-separated eccentric portions, means supporting one of said jaw members, at a point remote from said hinged connection, from one of said eccentric portions, a rigid strap journalled on the other of said eccentric portions, a trunnion element having a crank journal mounted on said other jaw element at a point remote from said hinged connection for turning movement relative

to said other jaw member about an axis parallel with the axis of said rotor, said strap having a journalled connection with said trunnion crank, toggle means carried by said other jaw member and including an arm fixed to said trunnion element, step-by-step means driven with said rotor, and means actuated by said step-by-step means, after a predetermined cycle thereof, to shift said toggle means from one limiting position thereof to the opposite limiting position thereof to vary the action of said jaw members.

5. The machine of claim 4 including means for varying the extent of the cycle of said step-by-step means.

6. In a machine of the character described, a pair of jaw members, means hingedly joining said jaw members for relative movement about a transaxially-movable axis, a rotor journalled for rotation about a fixed axis and having two peripherally-spaced eccentric portions, means supporting that end of one of said jaw members which is remote from said hinged axis from one of said eccentric portions, means supporting that end of the other of said jaw members which is remote from said hinged axis from the other of said eccentric portions, one of said jaw-end supporting means including adjustable means for varying the effective length thereof to vary the action of said jaw members, step-by-step mechanism, driven in synchronism with said rotor, for actuating said adjustable means at the end of its cycle, means for driving said rotor, including a differential transmission, said transmission including an input shaft, an output shaft, a housing, gears carried by said shafts and said housing and meshing to transmit motion from said input shaft to said output shaft, and means dominated by said step-by-step mechanism for periodically driving said housing to modify the motion transmitted from said input shaft to said output shaft, thereby modifying the rate at which said rotor is driven relative to the velocity of said input shaft.

7. The machine of claim 6 in which said last-named means comprises a single-revolution clutch driven from said input shaft, crank means driven through said single-revolution clutch, a rack mounted for reciprocation and operatively connected to said crank means, a gear meshing with said rack, clutch means providing a one-way drive connection between said gear and said differential housing, and means actuated by said step-by-step mechanism for tripping said single-revolution clutch.

8. The machine of claim 7 including means for varying the throw of said crank means.

9. The machine of claim 7 in which said crank means includes a shaft operatively connected to said single-revolution clutch to be driven therethrough, an element fixed to said shaft and projecting radially therefrom, said element providing a trackway extending longitudinally thereof and coplanar with the axis of said shaft and having a portion registering with said shaft axis, trunnion means guided for movement along said trackway into and out of coaxial alignment with said shaft, and means for securing said trunnion means in any desired position of adjustment along said trackway, said rack being operatively connected to said trunnion means.

10. The machine of claim 9 in which said means for securing said trunnion means comprises a lever mounted intermediate its ends to swing about an axis rotatable with said shaft, a collar coaxial with said shaft and shiftable

axially relative thereto, means providing an operative connection between said collar and one arm of said lever, means providing an operative connection between the other arm of said lever and said trunnion means, and means for shifting said collar and for holding the same in any selected position of adjustment.

11. The machine of claim 10 in which said means for shifting said collar comprises a screw shaft journalled for rotation upon an axis parallel with the axis of said shaft but held against axial movement, and a yoke threadedly connected with said shaft and operatively connected with said collar.

12. In a machine of the class described, a first jaw member, a second jaw member, a rotor having diametrically-opposed crank portions, means supporting an end of said first jaw member from one of said crank portions, means supporting the corresponding end of said second jaw member from the other of said crank portions, hinge

means joining the other ends of said jaw members, and means for movably supporting said hinge means comprising a trackway lying substantially in a plane normal to the axis of said rotor and having a portion inclined toward said rotor axis and toward a plane including the axis of said hinge means and lying between said jaw members, and means fixed with respect to said first jaw member supported and guided for reciprocal movement along said trackway.

EDWARD SKILLMAN.
